UNITED STATES PATENT OFFICE.

ERNEST L. FARROW, OF CLEVELAND, OHIO, ASSIGNOR TO THE CLEVELAND WIRE SPRING COMPANY, OF CLEVELAND, OHIO, A CORPORATION OF OHIO.

SPRING-MATTRESS.

1,097,408.

Specification of Letters Patent. Patented May 19, 1914.

Application filed December 13, 1913. Serial No. 806,407.

To all whom it may concern:

Be it known that I, ERNEST L. FARROW, a citizen of the United States, residing at Cleveland, in the county of Cuyahoga and State of Ohio, have invented certain new and useful Improvements in Spring-Mattresses, of which the following is a specification.

This invention relates to improvements in spring mattresses, and the improvement comprises adjustable side extensions for the mattress constructed and arranged substantially as herein shown and described and more particularly pointed out in the claims.

In the accompanying drawings, Figure 1 is a plan view of a spring mattress embodying my improvement, and Fig. 2 is a cross section of the mattress showing it mounted upon the side rails of a bed. Fig. 3 is a perspective view of one corner of the mattress, and Fig. 4 is a similar view showing a connecting bar for both the outer and inner ends of the stirrups or hangers. Figs. 5 and 6 are perspective views of modifications of the invention.

The mattress comprises a rectangular frame A of fixed dimensions surmounted by coiled springs B and a woven wire top C having a heavy wire border D of still larger dimensions than frame A. The border pieces 2 and the cross-piece 3 of frame A are of angle-iron, and corner braces 4 and a central connecting strip 5 make the structure rigid, all the pieces being riveted or otherwise united when overlapped or intersected.

The border pieces 2 at the sides of the frame have slots 5 at intervals in their vertical flanges, and the cross-pieces 3 and the end border pieces 2' have slots 6 in their vertical flanges at points relatively near the juncture of said cross pieces with the side border pieces. A flat bar 7 extends through slots 6 at each side of the frame and each bar 7 is free to slide transversely of the frame, said slots being sufficiently elongated for this purpose. The ends 8 of bars 7 are bent downwardly to prevent end movement and to secure the bars in place, see Fig. 3.

The stirrups or hangers 9 which provide adjustable side extensions to support the mattress frame on the side rails E of a bed, comprise flat strips of metal secured at their inner ends to the bar 7 and fashioned into hooks 10 at their outer ends, and the horizontally-extended inner end of each hanger 9 passes through a slot 5 in the border piece

and rests slidably therein as shown. All the stirrups 9 at each side of the frame are mounted in the same manner and connected to a single bar 7 and it is a very simple operation to adjust and hook all the stirrups 60 at one side of the frame to the bed rail as all are jointly movable. The support afforded by the hooks is also uniformly distributed the full length of the frame at each side thereof.

In Fig. 4 I show a connecting bar 11 uniting all the hook ends 10 of the stirrups at the same side of the frame, and this connecting bar may be a flat strip as shown in Fig. 3 or an angle-bar as shown in Fig. 6, and is 70 supplemental to the connecting bar 7 at the inner ends of the stirrups. In Fig. 5 I show a stirrup 12 having a twisted and slotted inner end 13 slidably sleeved over a round bar 14 fixed in the cross pieces 3, and a connecting bar 15 is riveted to the upright bent portion 16 of each stirrup to obtain the desired joint movability of all the stirrups 75 alined at the side of the frame and to brace and fix them in alinement with each other 80 and the frame.

In Fig. 6 I show a still further modification of the invention, the stirrups 17 being slotted at their ends and slidably connected by bolts or rivets 18 with a bar 19 fixed in 85 the cross pieces 3 of the frame, and the outer ends 20 of the stirrups being connected and formed into hooks by an angle bar 21.

What I claim is:

1. A bed mattress comprising a rigid 90 frame, hook members slidably engaged at intervals with said frame at opposite sides thereof, and a connecting bar united with all the hook members at each side.

2. A bed mattress comprising a rigid 95 frame, a set of stirrups having slotted ends slidably engaged with the frame, and a rigid connecting bar for all said stirrups.

3. A bed mattress comprising a rigid 100 frame having bars lengthwise thereof at each side, stirrups slidably engaged at intervals with the said frame and connected with said bars, and connecting bars united with said stirrups.

In testimony whereof I affix my signature 105 in presence of two witnesses.

ERNEST L. FARROW.
